STEPLADDER OR THE LIKE

Roy A. Cramer, Kansas City, Mo.

Application February 3, 1950, Serial No. 7,690

Term of patent 14 years

(Cl. D15—8)

To all whom it may concern:

Be it known that I, Roy A. Cramer, a citizen of the United States, residing at Kansas City, in the county of Jackson and State of Missouri, have invented a new, original, and ornamental Design for Stepladder or the like, of which the following is a specification, reference being had to the accompanying drawing, forming part thereof.

Fig. 1 is a perspective view of a stepladder or the like showing my new design.

Fig. 2 is a top plan view thereof.

Fig. 3 is a side elevational view of the device.

Fig. 4 is a front elevational view of the device.

I claim:

The ornamental design for a stepladder or the like as shown.

ROY A. CRAMER.
